UNITED STATES PATENT OFFICE.

THOMAS J. HART, OF BUFFALO, NEW YORK, ASSIGNOR, BY MESNE ASSIGNMENTS, TO LIBERTY MANUFACTURING COMPANY, OF PITTSBURG, PENNSYLVANIA.

TUBE OR FLUE CLEANER.

SPECIFICATION forming part of Letters Patent No. 761,586, dated May 31, 1904.

Application filed October 2, 1902. Serial No. 125,634. (No model.)

To all whom it may concern:

Be it known that I, THOMAS J. HART, a citizen of the United States, residing at Buffalo, in the county of Erie and State of New York, have invented new and useful Improvements in Tube or Flue Cleaners, of which the following is a specification.

This invention relates to a steam-boiler tube or flue cleaner of that class in which the scale-removing devices or cutters are carried by a head which is rotated by a turbine-wheel actuated by fluid under pressure delivered to the turbine-wheel through a hollow tube or pipe, which is connected to the cleaner and serves as the handle for manipulating the cleaner while in operation.

The object of the invention is to provide a tube or flue cleaner of simple, strong, and compact construction in which the turbine-wheel and head rotated thereby are flexibly connected with the body of the cleaner, whereby they can assume an angular position relative to the body and the device can be operated in tubes or flues having comparatively sharp or abrupt curves or bends.

In the accompanying drawings, Figure 1 is a longitudinal sectional elevation of a tube or flue cleaner embodying the invention and showing in section a portion of a curved tube or flue in which the cleaner is placed. Fig. 2 is a transverse section through the cleaner in line 22, Fig. 1. Fig. 3 is a transverse section through the turbine. Fig. 4 is a section through the turbine in line 44, Fig. 3. Fig. 5 is a section through one of the scale-cutters in line 55, Fig. 1. Figs. 6 and 7 are respectively a fragmentary longitudinal sectional elevation and a transverse section in line 77, Fig. 6, showing a slightly-different form of cleaner. Figs. 8 and 9 are similar views of another form of the cleaner.

Like letters of reference refer to like parts in the several figures.

Referring particularly to Figs. 1 to 5 of the drawings, A represents the hollow body or casing of the cleaner which carries the turbine and which is connected to the forward end of a tube or pipe B, which serves as the manip-

ulating-handle for the cleaner and the conduit for the actuating fluid for the turbine-wheel. The pipe B is preferably a flexible hose or tube and is connected to the casing A by a universal joint b of any usual or suitable construction. When the device is operated, the tube B is connected to a source of supply of water under pressure, steam, compressed air, or other moving fluid. C represents the turbine-shell, which is movably mounted in the body or casing A and which carries the turbine-wheel and the scale-cutters. The turbine-shell is universally mounted in the body or casing in such a manner that the shell can tilt or assume an inclined position in any direction in the body or casing. In the construction shown in Fig. 1 the turbine-shell is provided with an enlarged front portion, the periphery of which is of convex spherical curvature, as indicated at c, and this spherically-curved portion bears in a corresponding concave spherically-curved surface d at the front end of the body or casing. This surface d is formed on the casing and a ring D, which is screwed on a threaded portion of the body or casing and which is preferably held from turning or disengagement therefrom by a lock-screw d' or other suitable means. A stop is provided for limiting the angular movement of the turbine-shell in the casing. In Fig. 1 this stop is in the form of lugs E or arms projecting radially from the rear reduced end of the shell and adapted to engage the inner wall of the casing or body. F represents the turbine-wheel, which may be of any usual construction and which is journaled in a cylindrical chamber f, formed in the front end of the turbine-shell. The turbine-wheel shown is provided with inclined radial blades and is preferably journaled on ball-bearings in the following manner: f' represents a central shaft, which is secured rigidly to the turbine-shell and projects forwardly therefrom through a central hole of the turbine-wheel and its forwardly-projecting hub f''. The turbine-wheel is provided on its rear side with a cone, which bears on a circular row of balls f''' in a ball-cup carried by the shell. The for-

ward end of the shaft is provided with a cone which bears on a circular row of balls f^4 , located in a ball-cup carried by the hub of the turbine-wheel. The turbine-wheel may be 5 journaled in any other suitable manner. f^5 represents ports which extend through the turbine-shell, preferably at an angle, as indicated in Fig. 4. These ports communicate in 10 all positions of the turbine-shell with the interior chamber or hollow of the casing A, so as to deliver the motive fluid to the blades of the turbine to rotate the latter. H represents the scale-cutters or cleaning devices. 15 These cutters are of the usual form, consisting of hardened steel, toothed or serrated, disks h , which are mounted on a journal h' . Each cutter-journal projects forwardly from the forward end of a swinging arm h^2 , which is pivoted at its rear end to lugs h^3 on the hub 20 of the turbine-wheel. When the turbine-wheel is rotated, the arms are thrown outwardly by centrifugal force to cause the cutter to strike and remove the scale on the interior of the tube or flue. The outward movement 25 of the arms is limited by their rear ends engaging with the hub of the turbine-wheel. The manner of securing the cutter-journals to the arms is preferably as follows: The journal passes through a longitudinal circular hole h^4 in the arm, the rear end of the 30 journal having a flat face or shoulder h^5 , which bears flat against a coöperating flat face or shoulder on the swinging cutter-arm. h^6 represents a key or cotter-pin which passes 35 through registering holes in the journal and arm. By this construction the retaining-pin can be readily removed and the journal detached from the arm; but the journal cannot turn in its bearing-hole and shear off the pin. 40 In the construction shown in Figs. 6 and 7 the turbine-shell I is provided at its front end with a convex spherical surface which bears in a concave spherical surface formed in a ring i , secured to the casing i' of the cleaner. 45 The reduced rear end of the turbine-shell is also spherically curved and bears in a concave spherical face formed on a diaphragm or bridge i^2 , which extends across the chamber of the casing. The bridge or diaphragm is 50 provided with one or more openings i^3 for the passage of the actuating fluid for the turbine, and the turbine-shell is provided with suitable delivery ports or passages for directing the fluid against the blades of the turbine-wheel. 55 In the construction shown in these views, Figs. 6 and 7, the stop for limiting the angular movement of the turbine-shell consists of an angular flange or rib j on the bridge or diaphragm which surrounds the reduced rear 60 portion of the turbine-shell and against which the latter is adapted to strike. This construction affords a greater bearing-surface in the cleaner-casing for the turbine-shell.

In the construction shown in Figs. 8 and 9 65 the turbine-shell, as in the construction shown

in Figs. 6 and 7, is provided with a large front portion having a universal bearing in the front part of the casing and a rear reduced portion k , which has a convex spherical face bearing on a concave spherical face k' , formed in a disk or plate K. This disk K, which is of smaller diameter than the chamber in the casing k^2 of the cleaner, so as to leave an annular passage around the same for the turbine-actuating fluid, is not fixed to the casing of the cleaner, but is supported in the following manner: The forward end of the tubular handle B' of the cleaner or the coupling which connects the same with the casing is provided with a hollow spherical forward end or head L. This spherical head is held in the cleaner-casing by a ring l , which is screwed on the rear end of the casing around the spherical head in said ring and is free to move universally in said ring. The forward portion of the spherical head L bears in a concave spherical face formed in the rear side of the disk K. Owing to the opposite curvature of the bearing-faces on the disk for the turbine-shell and the spherical head L, the disk 90 is held from movement. The disk properly retains both the turbine-shell and the spherical head L in their proper relation in the cleaner-casing. The spherical head L is provided with one or more holes l' for the passage of the motive fluid. In this construction the disk K is provided with an annular flange m , against which the reduced rear portion of the turbine-shell is adapted to strike to limit the movement of the latter. The form of the device shown in Figs. 8 and 9 provides a very compact construction in which the casing is universally connected to both the turbine-shell and the end of the pipe or tubular handle for the device. 95

In the several forms illustrated in the drawings the turbine-shell, together with the turbine-wheel and the scale-cutters, which are carried by the shell, is capable of universal movement in the casing of the cleaner, so that the head can assume any necessary angular position relative to the casing to enable the cleaner to be readily passed through and operated in a tube or flue having comparatively sharp bends or curves. This construction also permits the turbine-wheel and cutters to move to one side and pass a projecting portion of a scale which has not been removed when the device is being removed from the tube or flue. 100

The turbine-wheel could be universally mounted in a fixed shell or casing; but the movable shell shown is preferred, as the correct relative position of the wheel-blades and fluid-ports in the shell is always maintained 105 regardless of the position of the wheel.

I claim as my invention—

1. The combination of a supporting-body, a turbine-wheel loosely mounted on said body and adapted to assume an angular position 110

- relative thereto, one or more flue-cleaning devices connected to said turbine, and means for conveying an operating fluid to said turbine-wheel, substantially as set forth.
- 5 2. The combination of a hollow casing, a turbine-shell loosely mounted in said casing and adapted to assume an angular position relative thereto, a turbine-wheel journaled in said turbine-shell, a flue-cleaning device connected to said turbine-wheel, and means for conducting a motive fluid to said turbine-wheel, substantially as set forth.
- 10 3. The combination of a hollow casing, a turbine-shell loosely mounted in said casing and adapted to assume an angular position relative thereto, a turbine-wheel journaled in said turbine-shell, a flue-cleaning device connected to said turbine-wheel, means for conducting a motive fluid to said turbine-wheel, 15 and a stop for limiting the movement of the turbine-shell, substantially as set forth.
- 15 4. The combination of a hollow casing, a turbine-shell universally mounted in said casing and provided with fluid-ports communicating with the chamber of said casing, a turbine-wheel journaled in said turbine-shell, cutters pivoted to said turbine-wheel, and means for conducting an operating fluid for said turbine to said casing, substantially as 20 set forth.
- 20 5. The combination of a hollow casing, a turbine-shell provided with a convex spherical surface bearing on a concave spherical surface in said casing, and provided with fluid-ports, a stop for limiting the movement 25 of said turbine-shell in said casing, a turbine-wheel journaled in said turbine-shell, one or more flue-cleaning devices connected to said turbine, and means for conducting an operating fluid to said turbine, substantially as set 30 forth.

6. The combination of a hollow casing, a turbine-shell provided with a convex spherical face bearing on a concave spherical surface provided in said casing, said turbine-shell 45 having a convex spherical surface at its inner end, and a part supported in said casing and provided with a concave spherical surface on which said convex spherical surface at the inner end of said turbine-shell bears, substantially as set forth.

7. The combination of a hollow casing, a turbine mounted in one end of said casing and movable to assume an angular position relative thereto, a hollow tube movably mounted 55 in the opposite end of said casing, and a common device for retaining said turbine and said tube in position in said casing, substantially as set forth.

8. The combination of a hollow casing, a 60 turbine-shell universally mounted in one end of said casing and provided with a convex spherical surface, a turbine-wheel in said shell, a tube having a spherical head movably mounted in the opposite end of said casing, 65 and a disk arranged between said turbine-shell and spherical head, and provided on opposite sides with concave spherical surfaces on which said turbine-shell and spherical head bear, substantially as set forth.

9. The combination of a cutter, a journal therefor, an arm provided with a hole in which said journal engages, coöperating flat faces on said journal and arm, and a pin connecting said journal and said arm, substantially as set forth.

Witness my hand this 23d day of September, 1902.
